United States Patent Office

Des. 178,260
Patented July 10, 1956

178,260

LAUNDRY MACHINE

Frederick W. Perl, Mansfield, Ohio, and Lurelle V. A. Guild, Noroton, Conn., assignors to Westinghouse Electric Corporation, East Pittsburgh, Pa., a corporation of Pennsylvania

Application January 26, 1956, Serial No. 39,916

Term of patent 14 years

(Cl. D49—1)

The single figure of the drawings is a perspective of a laundry machine embodying the new design.

The dominant features of the design are shown in full lines.

We claim:

The ornamental design for a laundry machine, substantially as shown and described.
